UNITED STATES PATENT OFFICE.

FRANKLIN J. GUSTINE, OF NEW ORLEANS, LOUISIANA.

TROLLEY CATCHER AND RETRIEVER.

No. 879,257.

Specification of Letters Patent.

Patented Feb. 18, 1908.

Application filed July 5, 1906. Serial No. 324,361.

To all whom it may concern:

Be it known that I, FRANKLIN J. GUSTINE, a citizen of the United States, residing at New Orleans, in the parish of Orleans and State of Louisiana, have invented certain new and useful Improvements in Trolley Catchers and Retrievers; and I do hereby declare the following to be a full, clear, and exact description of the invention, such as will enable others skilled in the art to which it appertains to make and use the same.

This invention relates to improvements in trolley catchers and retrievers and especially to that type wherein mechanism is automatically tripped at a certain position in the upward travel of the trolley pole towards a vertical position, so that the pole will fall by gravity below the trolley wire, in which position it is locked against movement.

To more fully understand the invention, reference is had to the accompanying drawings illustrating a practical embodiment of the same, in which like letters designate the same parts in the several views, and in which:

Figure 1 shows a fragmentary view of a car, the several positions of the trolley pole being indicated. Fig. 2 is a side elevation, with the casing or cover removed and showing the parts in their normal set position. Fig. 3 is a similar view, showing the several parts interlocked after the trolley has jumped the wire and been retrieved. Fig. 4 is a similar view, showing the position of the several parts when the trolley pole is drawn down to reset the mechanism. Fig. 5 is a fragmentary view in side elevation of a lower part of the trolley pole looking from the opposite side to that shown in the prior figures. Fig. 6 is an edge view of same, and Fig. 7 is a fragmentary view, showing a different form of spring connection between the trolley pole and tripping mechanism.

1 designates a plate forming one wall of a casing, and 2 the trolley pole pivoted to said plate as by the bolt 3. The end of the trolley pole is provided with a tail-piece 4, which is preferably of the construction clearly illustrated in Figs. 5 and 6, wherein 5 and 6 are off-sets or enlargements, the off-set 6 being adapted to engage certain mechanism and the off-set 5 being provided with a cam face 7, a notch 8 and an apertured lug 9, all as hereinafter referred to.

Pivoted to the plate 1, as at 10, is a trip bar 11 having a laterally projecting lug 12

and curving at its free end and extending into proximity with said offset 5 and adapted to be engaged by the cam face 7 thereof. This trip bar 11 is provided with a spring 13 tensioned to pull said bar upwardly.

14 and 15 are a pair of oscillating arms pivotally connected to said plate as at 16 and at their free ends pivotally connected by the cross link 17. The peripheral face of the enlarged pivoted end of the arm 14 is notched as at 14^a, seen most clearly in Fig. 3.

18 is a curved detent pivotally connected to said plate 1 and 19 is a link bar pivotally connected at respective ends to the free end 70 of said curved detent 18 and said oscillating arm 15.

20 designates a suitable spring or springs interposed between the upper end of said oscillating arm 15 and the apertured lug 9. 75

In the form shown in Fig. 7 a slightly modified arrangement of the spring connection is illustrated. In this figure a spring 21 of the compression type is employed, 22 designating a casing for said spring, and 23 a headed bolt engaging one end of said spring and adjustably connected at its other end to the upper end of said oscillating arm 15, in any suitable way, such as by a screw threaded connection. Of course it will be understood that in this construction the casing 22 will be suitably connected to the trolley pole.

In operation, referring first to Fig. 2, it will be observed that when the parts are in the position shown, the tripping bar 11 is held in its uppermost position by the spring 13 with the lug 12 engaging the notched portion 14^a of the oscillating arm 14, and at the same time the upper end of the bar 11 is disposed beneath the cam face 7. In this position the arm 15, the link bar 19 and detent 18 are also locked against movement. This is the normal running position of the parts when the trolley is on the trolley wire.

As soon as the trolley jumps the wire, upon the upward movement of the pole, the cam face 7 engaging the tripping bar 11, forces said bar downwardly and prior to the pole reaching a vertical position the lug 12 having been lowered out of engagement with the notched portion 14^a of the arm 14, the tension of the spring having been removed, the trolley pole will drop until its weight and the force of its fall is exactly counterbalanced by the engagement of cam 4 with the arm 14 110 and through bar 17 and arm 15 which re-applies the tension to the spring 20. After

reaching the lowest point to which the pole drops, shown in Fig. 4, the said pole will rebound until it reaches some such position as that shown in Fig. 3, and when this happens 5 the detent 18 enters the notch 8 and locks the pole against upward movement.

To re-set the mechanism when the trolley is to be placed on the wire again, the trolley pole is pulled downwardly to the position 10 shown in Fig. 4, during which movement the off-set 6 of the tail-piece 4 riding along the edge of the arm 14 forces said arm and the parts connected therewith rearwardly to their normal position, whereupon the lug 12 15 springs behind the notch 14^a and the parts are thus again locked, when the trolley pole may be elevated to engage the trolley wire.

Having thus described the invention, what I claim is:—

20 1. In a trolley catcher and retriever, the combination with a trolley pole, of an oscillating arm, a spring interposed between said arm and pole, a pivoted detent adapted to engage a notch formed on said pole, a link 25 bar pivoted at its ends to and connecting said detent with said oscillating arm, means for locking said oscillating arm against movement, and automatic means for tripping said arm for releasing the tension on said spring 30 and forcing said detent into interlocked engagement with said trolley pole, substantially as described.

2. In a trolley catcher and retriever, the combination with a trolley pole, of an oscillating arm, a spring interposed between said pole and arm, a tripping bar extending adjacent the base of said trolley pole, means disposed between said tripping bar and oscillating arm and coöperating to lock said arm 35 against movement, the base of said trolley pole being adapted to engage said tripping bar and release said oscillating arm upon the trolley pole jumping a trolley wire, substantially as described.

25 3. In a trolley catcher and retriever, the combination with a trolley pole, of an oscillating arm, a spring interposed between said pole and arm, a tripping bar pivoted at one end to a rigid support and at its other end 40 extending adjacent the base of said trolley pole, means disposed between said tripping bar and oscillating arm and coöperating to lock said arm against movement, the base of said trolley pole being adapted to engage 45 and depress the free end of said tripping bar for releasing said oscillating arm upon the trolley pole jumping a trolley wire, substantially as described.

4. In a trolley catcher and retriever, the combination with a trolley pole, of a pair of oscillating arms, a spring interposed between said trolley pole and one of said arms, a link 50 connection between said arms, a trip bar coöperating with said arms to lock said arms against movement, and means for automat-

ically tripping said trip bar, substantially as described.

5. In a trolley catcher and retriever, the combination with a pivoted trolley pole provided with a tail-piece projecting beyond the 70 pivotal axis of said pole, an oscillating arm, a spring interposed between said arm and trolley pole, means for holding said arm locked against movement, and means for tripping said arm to release the tension on 75 said spring, said tail-piece being adapted to engage said oscillating arm upon a downward pull on the trolley pole and return said oscillating arm to its normal position, substantially as described.

6. In a trolley catcher and retriever, the combination with a trolley pole, of an oscillating arm provided with a boss having a notched periphery, means connecting said arm with said trolley pole and containing as 85 an element an interposed spring, a tripping bar provided with means adapted to engage said notched periphery of said boss and hold same locked when the mechanism is set, and means for operating said tripping bar when 90 the pole jumps the trolley wire, substantially as described.

7. In a trolley catcher and retriever, the combination with a trolley pole, of a pair of pivoted arms capable of oscillation, a link 95 connecting the free ends of said arms, means for locking said arms against movement, means for releasing said arms, a tail piece carried by the trolley pole adapted to operatively engage one of said arms for re-setting 100 the mechanism, and a spring interposed between said trolley pole and one of said arms, substantially as described.

8. In a trolley catcher and retriever, the combination with a trolley pole, of a pair of 105 pivoted arms capable of oscillation, a link connecting the free ends of said arms, means for locking said arms against movement, means for releasing said arms, a fixed tail-piece carried by the trolley pole adapted to 110 operatively engage one of said arms for re-setting the mechanism, and a spring interposed between said trolley pole and one of said arms, substantially as described.

9. In a trolley catcher and retriever, the combination with a trolley pole provided 115 with a notch at the lower end thereof, of an arm capable of oscillation, a spring interposed between said trolley pole and said arm, a pivoted detent, a link bar connecting the 120 free end of said detent with said arm, said detent coöperating with the notched trolley pole, when the trolley pole has been dropped, to lock said trolley pole against upward movement, means for locking said arm in 125 position with said detent out of engagement with said trolley pole, and means for releasing said arm upon the trolley pole jumping the wire, substantially as described.

10. In a trolley catcher and retriever, the 130

combination with a trolley pole, of a pair of pivoted arms capable of oscillation, a spring interposed between said trolley pole and one of said arms, a link connecting the free ends 5 of said arms, said trolley pole and one of said arms being each provided with a boss having a notched periphery, a pivoted detent, a link bar connecting the free end of said detent with one of said oscillating arms, said detent 10 coöperating with the notched boss of said trolley pole when the trolley pole has been dropped to lock said trolley pole against upward movement, a tail piece carried by said trolley pole and adapted to engage one of 15 said pivoted arms when the trolley pole has dropped to normally prevent a further lowering of same, and adapted to reset said arms and detent upon the further downward pull of said pole, and a tripping bar operating upon the trolley pole jumping the wire, said 20 tripping bar being provided with means co-operating with said notched boss of said oscillating arm to normally hold said parts interlocked, substantially as described.

In testimony whereof I affix my signature 25 in presence of two witnesses.

FRANKLIN J. GUSTINE.
